DESCRIPTION

FIG. 1 is a front perspective view of safety eye wear showing the new design for decorative nose bridge and lower frame elements;

FIG. 2 is a front view thereof;

FIG. 3 is a rear view thereof;

FIG. 4 is a top view thereof;

FIG. 5 is a side view thereof; and,

FIG. 6 is a bottom view thereof.

Broken lines form no part of the claimed design, and any shading is provided to illustrate contour only and is not an indication of texture, gloss, etc.

1 Claim, 3 Drawing Sheets
